THERMOSTATICALLY CONTROLLED LIQUID FUEL BURNER

Robert H. Hunter, Gates Mills, Abe J. Hanje, Cleveland, and Harris W. Smith, Parma, Ohio. (all of 1550 E. 17th St., Cleveland, Ohio)

Filed Dec. 31, 1954, Ser. No. 479,074

20 Claims. (Cl. 158—33)

This invention relates to liquid fuel burning devices, more particularly to torches of the type that project the fuel into a combustion supporting atmosphere from a nozzle, although the principles embodied in the invention have application in other types of fuel burners.

In the operation of burners that utilize pressurized fuel supply systems, the fuel is, in one arrangement, conditioned for burning by vaporization in a heated generator or in passing through a heat retaining fuel ejection member. Representative of this type of fuel burner is the conventional blow torch used by plumbers and steam fitters. One of the objections to vaporization of the fuel in a generator or by heating of the member from which it is projected is the necessity of using a special fuel that is completely vaporized by the heat in order to avoid leaving a residue in the passages of the member in which it is heated. Thus, it is impossible to use the common internal combustion engine fuels in conventional heat vaporizing torches, since such fuels customarily contain gums, resins, and additives such as tetraethyl lead that are deposited in the fuel vaporizing passages. Such deposits eventually render the burner inoperative, as does deposited carbon.

In another arrangement for burning liquid fuels containing non-vaporizable gums, resins or additives, the fuel is mixed under pressure with a small quantity of air so that the fuel-air mixture can be projected into a combustion supporting atmosphere and will maintain combustion, the small quantity of pre-mixed air being adequate to initiate combustion of the projected mixture in continuous fashion. A representative fuel burning torch of this pre-mixed air type is shown in co-pending application for patent, Serial Number 457,803, filed September 23, 1954, on Instant Flame Torch.

In the torch of the patent application referred to, the fuel is contained in a sealed metal tank or vessel. A charge of air under pressure is developed by a manually operated pump carried by the tank, the air being charged into the space above the fuel in the tank or vessel. Air thus held under pressure is led into a mixing chamber in a metal block that surmounts and is carried by the tank. Fuel is led into the same mixing chamber by a conduit that extends downwardly through the air and fuel to the bottom of the tank. One of the objections to the fuel-air mixture torch is the depletion of the air charge in the top of the tank, necessitating intermittent manual pumping or other replenishment, in order to keep the torch in operation.

It is, therefore, one of the principal objectives of the present invention to overcome the difficulties heretofore experienced with both the fuel vaporizing torch in which the vaporization is effected by heat and the fuel-air mixture torch in which a quantity of air is mixed with the liquid fuel before projecting the fuel into the combustion supporting atmosphere. More particularly, it is sought to provide a pressurized fuel burner in which many types of liquid fuel can be burned without objectionable depositing out of gums, resins or fuel additives by reason

2

of the vaporization of the fuel and in which instant ignition is obtained by use of a fuel-air mixture that can readily be changed to pure fuel projection after a brief initial starting period without extinguishment of the flame, thereby avoiding objectionable depletion of the air charge in the pressurized fuel container. In accomplishment of this objective, the invention provides for heating of the pressurized fuel under thermostatic control as the fuel travels to the projection orifice, the heating under pressure being regulated so as to accomplish partial, but not complete, vaporization of the fuel, thereby keeping gums, resins and fuel additives in the unvaporized liquid portion of the fuel that is carried along and projected through the nozzle orifice. The heat vaporized fraction of the fuel projected from the orifice into a combustion supporting atmosphere maintains combustion. The non-volatilized fraction of the fuel carrying gums, resins, additives and any other contaminants that would be deposited out if the vaporizable fuel were completely vaporized, is burned in suspension in the atmosphere after leaving the nozzle orifice, and carbon deposition is eliminated.

After a short initial warm-up period, immediately following the instant ignition of the fuel-air mixture projected from the nozzle orifice, the supply of pressurized air to the internal mixing chamber can be stopped, the burner continuing in operation with fuel only being projected from the nozzle orifice, this projected fuel comprising a helter-skelter mixture of the volatilized or vaporized fraction and the non-vaporized (liquid) fraction referred to.

Another object is to provide a fuel burner in which the control of the fuel heating is accomplished by a thermostatic element, preferably—but not necessarily—under the direct influence of the heated fuel moving to the discharge nozzle orifice. More particularly, it is sought to provide a thermostatic fuel heating control wherein one or more bi-metallic strips arranged to control the heating of the fuel are in direct heat exchanging relation to fuel flowing from a heating zone to the discharge nozzle orifice. As a specialized version of this aspect of the invention, the fuel heating one is provided by a member supported in the path of the burner flame, such member being formed to provide a fuel passage that constitutes part of the fuel conduit leading from a fuel source, such as the bottom of the pressurized container, to the fuel discharge orifice in the nozzle. A suitable thermal responsive element, such as the bi-metallic strip or strips referred to is disposed in or adjacent that portion of the path of the fuel located between the heating zone member and the discharge nozzle. The thermostatic element is so arranged as to shift the position of the heating zone member in the burner flame in response to temperature variations of the fuel flowing to the discharge nozzle. In this manner, the temperature of the fuel is maintained within a suitable temperature range which will effect partial, but not complete, vaporization of the fuel, all in accordance with the invention's objectives.

Another object is to provide a thermostatically controlled burner incorporating an adjustment for varying the heating control so that the temperature or temperature range of the fuel projected from the orifice of the nozzle can be varied by the operator to suit different fuels, different burning requirements, or different environment situations.

Another objective is to provide a burner of the fuel vaporizing type in which the fuel is traveled over a path of relatively small cross-sectional area during heating and, after heating, the transfer of heat to or from the heated fuel, as by contact with heat absorbing surfaces, is minimized so that the projection temperature of the fuel is held close to the temperature to which it is heated

in the heating zone. Pre-determined or pre-set fuel heating temperatures are thus maintained during protracted periods of torch operation, even though the heavy sectioned metal components of the torch may vary in temperature over relatively wide ranges. According to this aspect of the invention, and as a specialized objective, the discharge nozzle in which is formed the fuel projection orifice is carried by a metal element of low heat conductivity which, although rigidly secured to a high heat conductivity heavy sectioned member of the torch, has the effect of substantially insulating the nozzle from such high heat conductivity heavy sectioned component and thereby preventing objectionable heat transfer to or from the fuel such as cooling of the heated fuel moving into and through the nozzle during starting periods of the torch when the heavy sectioned metal component is likely to be at a relatively low temperature or overheating of the fuel when the heavy sectioned member becomes hot as a result of prolonged torch operation.

To further the specialized objective of insulating the fuel conduit which conducts the partially vaporized fuel to the projection orifice, the metal element which carries the discharge nozzle is insulatingly shielded from surrounding heat conductive members by an annular insulating air space.

Another objective is concerned with the fuel heating component of a vaporizing pressurized torch and contemplates an arrangement in which the fuel is heated in a member mounted for yielding movement into and out of the path of the torch flame, the mounting having a high degree of flexibility so that movement of the heating member is readily accomplished as by means of one or more bi-metallic strips with a high degree of sensitivity and accuracy in thermal response. In a specialized version of this aspect of the invention, the conduit for the fuel takes the form of a helical corrugated thin-walled metal tube of the bellows type. The use of such a tube in that portion of the fuel path extending from the heating zone member to the discharge nozzle permits placement of a suitable thermostatic element, such as the bi-metallic strip or strips referred to, within the central passage of such flexible bellows tube, blocking such passage. By suitable connections at the ends of the corrugated bellows tube, the heated fuel is introduced into the spiral passage defined by the helical corrugations of the tube at one end of the latter, and flows spirally about the bi-metal or other thermostatic element along the entire length of the latter. Thus, the thermostatic element is, in effect, wholly immersed in the heated fuel and completely subject to the temperature of the latter, so that accurate thermal response is obtain.

Another objective is concerned with the mounting of the fuel vaporizing heating component of a torch so as to be readily accessible for service and repair and yet adequately protected from damage. The invention contemplates, in furtherance of this objective, the placement of the fuel heater and the associated fuel conductors and thermal responsive means outside, preferably below, the burning tube of the torch, with the heating zone member that moves into and out of the flame path disposed at the discharge opening of the burning tube. A protective shield, or shroud, is arranged to enclose the major portion of the fuel heater and to extend forwardly beyond the heating zone member, so as to enclose the latter and prevent interference with its movements into and out of the flame path.

Other objects and advantages pertain to certain novel features of construction and combinations and arrangements of parts calculated to obtain a generally improved fuel burner of the pressurized fuel burning type, simple in design and construction, relatively inexpensive to manufacture and readily serviced and repaired in the field, all as will become apparent from the following detailed description of a suitable embodiment representing the best known mode of practicing the invention. This de-

scription is made in connection with the accompanying drawings forming a part of the specification.

In the drawings:

Fig. 1 is a fragmentary side elevational view, partly in section and with parts broken away and removed, showing a pressurized fuel burning torch embodying the principles of the present invention, and incorporating a thermostatically controlled fuel heater, the fuel containing tank being largely omitted in this view;

Fig. 2 is a vertical sectional detail through the mixing block of the fuel burning torch of Fig. 1, this view being enlarged with respect to that figure to show the tubular inlet and outlet leads of the fuel heater and the fuel discharge nozzle and related parts;

Fig. 3 is a horizontal sectional detail through the mixing block of the fuel burning torch of Fig. 1, this view being taken substantially on the line 3-3 of Fig. 1 and enlarged with respect to that figure;

Fig. 4 is a fragmentary detail, partly in section, and with parts removed showing the fuel heating element of the torch, this view being taken substantially along a line indicated at 4-4 of Fig. 1;

Fig. 5 is a foreshortened fragmentary sectional detail of the return run of the fuel heater comprising a flexible corrugated metal conduit, this view being enlarged to show the bi-metallic thermostatic control element and the end connections for such flexible conduit and being taken substantially along the line indicated at 5-5 of Fig. 4;

Fig. 6 is a transverse sectional detail through the flexible conduit comprising the return run of the heater, this view being taken substantially along the line indicated at 6-6 of Fig. 5;

Fig. 7 is a transverse sectional detail taken through the axis of the rotatable adjusting member that varies the position and heating characteristics of the fuel heating element, the location of this section being indicated at 7-7 of Fig. 4 and being enlarged with respect to that figure and also with respect to the other figures in which the adjustment means is shown;

Fig. 8 is a fragmentary sectional detail showing the plug through which the pressurized air is metered into the mixing chamber and the needle valve by which the pressurized air supply is shut off after the initial warm-up period, showing a fragmentary section of the mixing block and air supply orifice, this section being taken at line 8-8 of Fig. 3; and

Fig. 9 is a fragmentary front end elevational view of the torch, taken substantially along the line 9-9 of Fig. 1 and enlarged with respect to that figure.

Fuel and air supply

The thermostatically controlled fuel supplying and heating system of the present invention is useful in many applications in fuel burning devices requiring an arrangement for pre-heating the fuel before it is burned. One of the most useful applications of the invention is in connection with portable quick-starting torches of the type adapted to the burning of standard motor vehicle, aircraft, and other fuels containing non-volatilizable gums, resins, additives or similar ingredients. Since the pressurized fuel and air can be supplied to the mixing block and chamber in various ways, such as from independent storage tanks or from the storage tank of a vehicle and an air pump, the fuel and air source is indicated generally at 1 and here takes the form of a pressurized or hermetically sealed tank and related parts described in more detail in the referenced application. This tank may be drawn or fabricated of steel or other suitable sheet metal and, in its top wall 2, is fitted with a pump 3 by means of which atmospheric air is forced under pressure into the interior of the tank to provide the desired pressure. The pump is removable from its retaining ring or ferrule in the tank top to provide a filling opening through which the fuel is introduced into the tank con-

tainer 1 through the top wall 2. Air and fuel are led into mixing block 7 of the torch structure through a tubular coupling block 5 which is welded or otherwise secured to the top wall 2 of the tank over an opening therein, and a hollow plug 8 secured to the bottom face of the mixing block 7. The plug 8 is externally threaded and screwed into the internally threaded upper end of the tank mounting block 5.

Mixing block

The mixing block 7, of cast brass or bronze, is shown to be of rectangular or square section throughout the major portion of its length, having a reduced forward stub end 9 threaded externally to receive the internally threaded base end 10 of a circular sectioned elongated burning tube 11.

The other, or rear, end of the block 7 is formed with an integral axial extension 14 of circular section, which has an axial bore 15 that guides stem 16 of the main control valve. This valve is turned by a thumb-wheel 17 which is fastened on the stem 16, the stem having a reduced diameter inner end 18 threaded into a reduced diameter axial continuation of the bore 15. The tip of the valve stem 16 is formed with a reduced diameter cylindrical portion 19 that terminates in a conical tip 20 which engages a mating seat 21 (Fig. 3) and thus serving to seal mixing chamber 22 from a reduced diameter passage 23 which is aligned axially with the valve stem and continuous with the mixing chamber. An O-ring 25 is received in an annular groove in the peripheral surface of valve stem 16 and engages the walls of the cylindrical bore 15 to seal the valve stem bore and prevent the loss of pressurized fuel and air out of the valve stem opening.

The mixing block 7 is formed with a transverse threaded bore 26 that receives and at its ends is sealed by fuel and air metering plugs 27 and 28 respectively. The axis of the bore 26 intersects the axis of the valve stem bore, the transverse bore being located immediately adjacent the conical valve seat 21 so that the central part of the transverse bore between confronting inner end faces 29 and 30 of the metering plugs 27 and 28 defines the mixing chamber 22 for the pressurized fuel and air. Fuel is led into the mixing chamber 22 from the bottom of the pressurized tank 1 through a supply tube 32 which may be of metal press-fitted or brazed into a socket 33 that opens through the bottom of the block into the interior of the tubular attaching plug 8. A bore 34 continuous with the tube socket 33 leads into the transverse threaded bore 26 at a point removed from the mixing chamber 22. The opening of the bore 34 into the transverse threaded bore 26 is indicated at 35 (Fig. 3) and communicates with an annular chamber 36 surrounding a reduced portion 37 of the fuel metering plug 27, the threadal engagement of the fuel plug 27 with the axial bore 26 serves to seal the annular chamber from the mixing chamber 22. From the annular chamber 36, the fuel is led through a radial metering passage 38 in the reduced portion of the plug 27 into a central axial passage 39 of the plug. The radial metering passage 38 is exaggerated in size for clarity, it being in practice about .01 inch to about .02 inch in diameter. The axial passage 39 is closed at its outer end and at its inner end is formed with an opening located to direct fuel into the mixing chamber and against the reduced portion 19, or an adjacent frusto-conical portion 40 of the valve stem 16.

Air under pressure from the tank or container 1 is led into the transverse threaded bore 26 at the end of the latter remote from the fuel inlet opening 35. The air enters the mixing block 7 through a drilled hole or bore 42, the lower end of which opens into the interior of the threaded plug 8 and the upper end of which has an opening 44 that communicates with an annular chamber 45 surrounding reduced portion 46 of the air metering plug 28. A radial passage 47 (Fig. 8) in the reduced plug

portion 46 leads the air from the annular chamber 45 into an axial bore 48 of the plug 28. Like fuel chamber 36, chamber 45 is sealed from mixing chamber 22 by the threadal engagement of air plug 28 with the axial bore 26.

Air control

The air metering plug 28 incorporates valve means for regulating the supply of pressurized air to the mixing chamber 22. The valve here takes the form of a stem

10 50 turned as by a thumbwheel 51 fastened on its outer end. The stem includes a thread portion 52 engaged in an internally threaded reduced portion of the bore 48. The inner end of the stem 50 is further reduced in diameter and terminates in a conical tip 53 that engages a frusto-conical seat 54 to seal the plug passage 48 from a reduced axial orifice passage 49 that opens into the mixing chamber 22.

The radial metering passage 47 is exaggerated in size, being in practice of the order of about .03 to about .04 inch in diameter. The axial passages 39 and 49 in the fuel and air metering plugs may be about .031 inch in diameter, the figures given for the various passages being representative of a suitable arrangement for a torch having a capacity of about 25,000 B.t.u. per hour, using a commercial gasoline type fuel.

The outer end of the axial bore through the air metering plug 28 is counter-bored to receive, as by a sliding fit, the cylindrical portion of the stem 50 to which the thumb-wheel 51 is fixed. A deformable sealing gasket 56 embraces the stem and is compressed between the outer end face of an externally threaded guide extension 57 on the plug 28 and the bottom of a cap 58 that threadedly engages such guide extension.

35 Each of the metering plugs 27 and 28 is formed with an external hex, or other non-circular portion, to receive a wrench for tightening the plug into the threaded transverse bore or passage 26, the hex portions of the plugs providing circular radial shoulders that seat against the opposite side faces of the burner block 7 to seal the ends of the transverse bore 26. If desired, suitable gaskets (not shown) may be disposed between the burner block and the hex portions of the plugs to insure fluid-tight seals.

Fuel circuit and nozzle

45 46 The fuel forced into the axial passage 23 of the burner block 7 from the mixing chamber 22 when the needle valve cone 20 is backed away from the seat 21 is passed through a thermostatically controlled heating device or element with which the present invention is particularly concerned. A transverse bore 59, closed at its inner end, intersects closed axial passage 23, and provides a passage-way to the receiving end of a conduit 60, which is press fitted or brazed into the counter-bored outer end of the bore 59.

50 55 The tube 60, which may take the form of a standard soft copper tube of a nominal $\frac{1}{8}$ inch outside diameter, leads into the forwardly extending run of the fuel heating device or element indicated generally at "T." The return run of the heating device terminates in another tubular metal conduit 61, which may also comprise a standard soft metal copper tube of nominal $\frac{1}{8}$ inch outside diameter. This return conduit 61 carries the heated fuel to a nozzle support 62 mounted in an axial chamber 63 formed in the forward end of the burner block 7, the chamber 63 opening axially into the interior of the burning tube 11 at the base end of the latter.

56 60 65 To minimize conduction of heat to and from the fuel moving to nozzle 64, which is screwed into the bored and internally threaded outer end of the support 62, the support is formed of metal having relatively low heat conductivity, such as commercial stainless steel. To further reduce the heat transfer between fuel moving to the nozzle through the support 62, the support is mounted cantilever fashion in the chamber 63 by attaching the base

end only of the support to the bottom of the recess, this attachment being effected as by threading, press fitting, or brazing. In the arrangement shown, the burner block 7 is formed with an axial socket that matingly receives the end of the support 62 so as to locate the parts in assembly. The support 62 may be of circular cross section, and mounted so its external surface is concentric to the internal cylindrical surface of the recess 63 in the provision of an annular insulating air space 65 that completely surrounds the support.

The nozzle 64 includes a hex or other non-circular section portion, intermediate its ends, to receive a wrench or other turning tool in screwing the reduced threaded end 66 of the nozzle into internally threaded counterbore 67 in the outer end of the support. An axial bore 68 through the nozzle 64 opens through a relatively short axial extension 69 having diameter about equal to length formed on the face of the nozzle, the outlet of the bore 68 constituting the discharge orifice through which the fuel is projected axially into the interior of the burning tube 11. The return tube 61 from the heater extends into the recess 63 of the burner body 7 through a lateral opening 70 with surrounding insulating clearance and is press fitted, brazed or soldered into a lateral socket 71 bored in the support 62. The inner end of this socket intersects or otherwise communicates with an axial bore or passage 72 that is continuous with the nozzle receiving counterbore 67.

Fuel forced under pressure from the container 1 and mixed with air in the chamber 22 thus travels first to and from the heating device T and then into the nozzle support 62, from which it is projected into the interior of the burning tube 11 through the nozzle orifice. Within the tube 11, the mixture of fuel and air can be ignited instantly without any initial priming or warming, this being one of the characteristics of the instant flame torch of the application referred to. Air is supplied to the interior of the burning tube 11 through a series of circumferentially spaced large openings 75 located in the mid-section of the tube, and a series of circumferentially spaced relatively small openings 76 located adjacent in-turned circular flange 77 which defines circular discharge opening 78 at the extreme forward end of the burning tube.

Fuel heating system

The heating device or means by which fuel received through the tube 60 is heated and then returned to the structure of the burner block 7 through the tube 61 comprises a suitable heater and a suitable thermostatic element for regulating the fuel heating to maintain the temperature of fuel flowing to the nozzle through the return tube 61 within predetermined temperature limits and in a predetermined state or condition. The heating may be accomplished electrically or in any other suitable manner, the device of the present invention utilizing the heat of the torch flame. The heater thus may comprise a helical coil 80 of a metal having high heat conductivity such as, for example, standard copper tubing of approximately $\frac{1}{8}$ inch nominal outside diameter. This coil is mounted in the path of flame issuing from the discharge outlet 78 of the burning tube 11, the coil having its axis approximately parallel to the axis of the burning tube but displaced downwardly from such axis. To improve the heating action, a number of sheet metal vanes 81 are secured, as by soldering or brazing, each to an upper portion of one of the turns of the helix 80, these vanes being angled toward the source of the flame so as to deflect the flame toward and against the tubing constituting the coil.

The two ends of the coil 80 are suitably connected, one to the fuel supply tube 60 and the other to the fuel return tube 61, in the provision of a closed path of small cross section over which fuel travels away from the burner block assembly and returns thereto after having passed through a heating zone member comprising the coil 80.

By suitable positioning of the coil 80 in the flame path the heating of the fuel passing through such coil can be regulated as desired to obtain optimum burning temperature and optimum vaporization of the fuel. It is proposed to subject a thermal motor, such as a bi-metallic strip or strips, to the influence of liquid fuel returning to the burner block assembly and the nozzle 64, so that such thermal motor, in response to temperature variations of the returning fuel, alters the position of the heater coil 80 in accordance with a predetermined pattern.

Since the energy available to effect movements of the heating coil 80 is desirably held to a minimum, in order that the control can have high sensitivity and fast initial action, while yet being simple, compact, inexpensive and light-weight, the supply and return conduits or tubes 60 and 61 are connected to ends 84 and 85 of the heater tube 80 by flexible thin-walled bellows-type metal tubes 82 and 83 respectively. Each of the bellows tubes 82 and 83 is corrugated copper throughout its length, being formed with a continuous helical groove defining a continuous helical ridge or crest. The ends of the bellows tubes are received telescopically within tubular socket end fittings 87 and are secured in place as by soldering or brazing to provide fluid-tight joints. This attachment of the flexible bellows tubes to and between the ends of the copper tubes 60, 84, and 61, 85 is shown in Fig. 5 for the tube 83, it being understood that a similar arrangement is used for the tube 82. Each fitting 87 is in the shape of a cap or thimble, the large open end of which receives the flexible tubing. The closed end of the fitting is formed with a socket into which is secured the end of the appropriate copper tube or conduit, the fitting having a through opening placing the interior of one tube in communication with the interior of the other.

Thermal motor

Extending through the passage within the flexible conduit 83 and into the end fittings 87 is a thermal motor comprising a series of elongated bi-metal strips indicated at 91, 92, 93, and 94. These strips may be of the type sold by H. A. Wilson Company, Newark, New Jersey, under trademark Morflex, each having a thickness of the order of about .015 inch. The several bi-metal strips are disposed flatwise against one another and their edges 45 are trimmed to provide in the aggregate a substantially circular cross section which substantially fills the clear internal passage of the bellows tubing 83. By thus filling the center space in the flexible tubing, fuel entering the thermal motor component of the heating device through 50 the discharge tube 85 of the heater, this being the right-hand end of Fig. 5, is caused to flow over a path of relatively small cross sectional area. By reason of the restriction in area of the bellows tube passage, the flowing fuel tends to follow the helical path defined by internal 55 grooves or channels 95 of the flexible tubing 83. The fuel thus flows circumferentially about the bi-metallic motor comprising the strips 91-94, as well as longitudinally thereof, so that effective transfer of heat takes place between fuel and the bi-metal strips. Thus is assured 60 the thermal response of the bi-metal motor as an accurate indication of the temperature of the fuel discharged from the heater coil 80.

The movements of the thermal motor comprising the bi-metal elements 91-94 occur in a plane which in Figs. 65 1, 2, and 5, parallels the plane of the drawings and in Figs. 3, 4, 6, 7, and 9 is normal to the plane of the drawings. So that the forces applied to the cantilever heater structure by the bi-metal motor strips are confined to the vertical plane mentioned, the bi-metal strips 91-94 are held against turning or rotation within the flexible tube 83 as by a press fit, or by suitable interlocks (not shown) with the end fittings 87. While the thermal motor is illustrated as an assembly of a plurality of flat bi-metal strips disposed flatwise against one another, it is feasible, 70 75 of course, to employ a fewer number of bi-metal strips

than shown, or other thermal responsive means to effect the movement of the heater 80 into and out of the path of the torch flame. In the arrangement shown, it is desirable to secure the several bi-metal strips 91-94 together as by brazing at one end, so they are readily inserted into and held within the tube as a unit.

It is one of the characteristics of the instant flame torch referred to that the fuel-air mixture leaving the chamber 22 is conducted wholly through passages of relatively small cross sectional area. Apparently an undesirable separation of fuel takes place if the fuel-air mixture is passed through chambers or passages of large cross-sectional area. In the present torch, employing a circuitous path for the fuel between the mixing chamber 22 and the nozzle 64, precautions are taken to avoid the use of passages of large cross sectional area. The bi-metal motor or strips 91-94 reduce the effective cross sectional area of the return run tube 83, as previously described, and the interior of the flexible bellows-type forward run tube 82 is filled in a like manner with a suitable material 96 (Fig. 7) such as braided wire, steel wool, or the like, to reduce its effective cross sectional area and to provide capillary passages for carrying the fuel-air mixture.

Although the fuel heater is shown as a specialized structure comprising a $\frac{1}{2}$ inch diameter 5-turn helical coil of copper tubing, it is apparent that other heaters can be employed. The flexible helical bellows-type tubes 82 and 83 may, for example, be parts of a single U-shaped piece of such tubing, the bend of the U being extended upwardly, so as to project into the path of the torch flame in substitution for, and replacement of, the helical coil 80.

In order that the bi-metallic thermal motor comprising the strips 91-94 be responsive primarily to the temperature of the heated liquid fuel returning to the mixing block 7 from the heater coil 80, the return run of the fuel conduit is insulated as by a spiral wrapping 97 of a suitable material, such as asbestos fabric or tape. The forward run of the fuel conduit comprising the flexible tube 82 is also covered by a wrapping of insulating material 98, which also may be asbestos fabric or tape. Thus the heating of the fuel is largely restricted to the heating zone member or coil 80 which is movable into and out of the flame by the action of the thermal motor 91-94, even when the burner has become quite hot from long runs, and heat loss in return run 83 is limited when the burner is in a cold condition, as when first put in operation.

As a further heat barrier to protect the fuel heater against radiant heat from the forward end of the burning tube 11 and as a stop to prevent contact of the fluid conduits 82 and 83 with the burning tube, there is provided a metal shield 100 interposed between the outer surface of the burning tube and the supply and return runs of the fuel heating structure or element. Although the shield 100 of stainless steel may extend the entire length of the fuel burning tube 11, it is satisfactory if it be restricted to the forward portion, say about $\frac{1}{3}$ the length of the fuel burning tube, since it is such forward portion of the burning tube that becomes heated to the highest temperatures during operation of the torch. The shield 100 is concentric to the burning tube and has a circumferential extent sufficient to protect the fuel tubes 82 and 83 against the radiant energy from the sides as well as the bottom of the burning tube. In the arrangement shown, the shield covers about $\frac{1}{5}$ of the burning tube circumference. A pair of spaced rivets 101 extend through the shield 100 and through the wall of the burning tube, suitable spacers or washers being interposed between the shield and the burning tube surface to hold the shield away from the surface of the burning tube in the provision of an insulating air space and to permit the circulation of air therebetween.

Adjustment of thermostatic control

At their rear ends, the supply and return runs of the fuel heater conduits are held cantilever fashion by a combined supporting and adjusting structure, depending from the mixer block 7. This holding structure comprises a circular sectioned turning or yoke 102 of brass or similar metal screwed on a fixed stud 109. The yoke includes a small diameter central portion 103 received between the fuel tubes 82 and 83. These tubes are engaged between an upwardly directed annular radial surface 104 and a downwardly directed annular radial surface 105 on the turning or yoke 102. Surfaces 104 and 105 and portion 103 thus define an annular relief or channel which receives the fuel tubes to cause them to move as the turning yoke 102 is rotated and caused to move axially along the stud 109 with which it is threadedly engaged.

The stud 109 is screwed onto a threaded bore provided in the bottom of the mixer block 7. A lock nut 111 on the stud 109 may be tightened against the underside of the mixer block 7 to retain the stud in a pre-selected position. The adjusting yoke 102 is thus held firmly by the mixer block while being adjustable vertically. This rotation is effected manually and the turning may be formed at its lower end with a relatively large diameter wheel portion 110 having, say, a knurled periphery. Since the runs or tubes of the fuel heating device are confined between the flat surfaces 104 and 105 of the adjusting yoke, the raising or lowering of the yoke has the effect of raising or lowering the forward heater coil 80 and thus varying the position of the latter relative to the burning tube discharge opening 78 through which the torch flame is projected. Raising the adjusting yoke (and the fuel heating unit) has the effect of increasing the temperature to which the fuel is heated, whereas lowering the yoke (and the fuel heating unit) has the effect of lowering the fuel temperature. This adjustment is especially convenient in a hand-torch of the character illustrated, which, by reason of its portability, will be used in various locations where fuel characteristics will vary and where the ambient atmosphere in which the torch is used will differ widely in temperature. For normal operation in a temperate zone, using commercial gasoline as a fuel, the adjustment is effected so as to maintain a temperature of from about 280° F. to about 340° F. when the fuel is supplied under a pressure of from about 25 pounds to about 60 pounds per square inch gauge. More desirably, the temperature is held in the neighborhood of about 310° F. at a pressure of about 40 pounds per square inch gauge, this mode of operation producing partial, but not complete, vaporization of the fuel so that, while the flame is maintained, there is no objectionable deposit of gums, resins, or additives within the narrow passages of the heating element, nozzle support or nozzle. In the torch mentioned, operating under the conditions referred to, the diameter of the orifice in the nozzle 64 is about .016 inch diameter.

Shroud

As a protection for the fuel heating element, the forward portion of the burning tube 11 is enclosed in a shroud 115 formed of a suitable heat resistant material, such as stainless sheet steel. The shroud is conveniently formed by bending a flat piece of sheet metal into a closed band, or tube, which, in cross section, is pear or egg shaped, as shown in Fig. 9. The burning or flame tube 11 is disposed in the large portion of the pear shaped section, providing beneath the burning tube, a chamber portion 116 to accommodate the tubes 82 and 83 of the fuel heating element. The shroud is generally larger than and spaced outwardly from the burning tube, providing a clearance 117 between the outer surface of the burning tube and the inside surface of the shroud, this space being approximately $\frac{1}{8}$ inch in radial dimension in the hand torch illustrated. The sheet metal tube

from which the shroud is formed is cut away across the upper half of the burning tube rearwardly from a radial plane intermediate the large holes 75 and the small holes 76, thus exposing the rear portion of the upper half of the burning tube and a number of the large burning tube openings 75. Vertical edges 118 of the shroud define the cut-off plane mentioned. Lower side portions of the shroud rearwardly of the edges 118 are bent inwardly so that their upper horizontal edge portions lie flatwise against the opposite sides of the burning tube in the provision of attaching tabs 119 that are secured to the tube sides by screws 120. The forward portion of the shroud is thus supported cantilever fashion by the screws 120, the shroud having a forward edge 122 defining a front opening that lies in a vertical plane beyond or ahead of the heater coil 80.

Beneath the burning tube, the edges of the sheet metal comprising the shroud tube are secured together as by a lapped joint indicated at 123. The side portions of the shroud are formed with integral flanges bent toward one another across the front of the fuel heating element and secured together in a lapped joint 124, these flange portions providing a frontal wall 125 on the shroud. The bottom wall of the shroud is spaced sufficiently below the bottom of the burning tube to permit full vertical movement of the fuel heating element tubes 82 and 83 which may be deflected as to the broken line position of Fig. 1 by the thermal motor in withdrawing the heater coil 80 from the path of the torch flame, or substantially so. Thus, the shroud 115 may be of non-uniform section along its length and the chamber portion 116 that accommodates the tubes 82 and 83 of the fuel heater may be relatively shallow at its rear end and relatively deep at the forward end immediately below the heater 80 where the greatest deflection or amplitude of movement of the fuel heater occurs.

Circulation of air through the shroud 115 is induced by pressure reduction at the forward end of the burning tube resulting from the blast of the torch flame and, if desired, supplemental openings may be provided in the shroud, such as opening 126 in the bottom of the shroud immediately below the heater coil 80. Thus, air may be drawn into the shroud chamber through the bottom opening 126, as well as through bottom rear opening 127 through which extend the tubes 82 and 83 and arcuate opening 128 into clearance space 117.

Operation

In the operation of the thermostatically controlled burner described, the tank or container 1 is first charged with the desired liquid fuel, such as standard gasoline, kerosene, jet engine fuel, or the like, and then air is pumped into the tank over the space above the fuel. This provides the desired pressurized air charge that serves not only to force the liquid fuel into and through the fuel heating system and out the nozzle 64, but also supplies combustion air during the warm-up period. With the needle valve 53 backed off its seat to admit pressurized air from the container or tank to the mixing chamber 22 under the proportioning conditions provided by the fuel and air metering passages 38 and 47 in the plugs 27 and 28 respectively, the main control valve 20 is backed off the seat 21, defining the outlet opening from the mixing chamber to admit the fuel-air mixture into the mixing block passage 23 through which the mixture flows into the intersecting passage 59 and thence into the supply tube 60 of the fuel heating device or element. The fuel advances from the supply tube 60 through the forward run 82 into the inlet tube 84 of the heater 80. From the heater, the fuel enters the return run 83 through the heater discharge tube 85, and from the return run 83 the fuel is led into the nozzle support passage 70 through the return conduit 61. From the return conduit 61, the fuel is conducted through the passage 72 into the bored area 67, thence through the passage 68 in the nozzle 64

and projected from the end outlet opening of the passage 68, which constitutes the projection orifice, into the combustion chamber defined by the burner tube 11.

The fuel-air mixture thus projected from the passage 68 into the combustion chamber is in a condition which permits immediate combustion and immediate torch use. It is ignited by inserting a match or the like through one of the large holes 75 in the burning tube or through the opening 78 in the end of the burning tube. Fuel passing through the heating coil 80, located directly in the path of the flame, when the system is cold, immediately begins to heat and vaporize. As the fuel is thus vaporized in the heating coil 80 at an increasing rate, the mixture being projected from the orifice 68 progressively increases in fuel vapor content. As the percentage of fuel vapor increases, the quantity of air required to be pre-mixed with the fuel progressively decreases, and the operator may adjust thumb-screw 51 to gradually close the needle valve inner cone tip 53 against the seat 54 of the air control valve. When the rate of vaporization has reached the desired operational level, the air control valve 53 may be completely closed and the burner will continue in operation as a fuel-vapor burner. A few strokes of the pump 3 recharges the tank with air to replace that consumed during the short warm-up period. As the temperature of the fuel leaving the heating coil 80 approaches the desired range, and, consequently, the point of maximum desired vaporization, the bi-metallic motor elements 91-94 become heated and cause flexible conduit 83 to bend and move the heating coil 80 downwardly away from the axis or center of the torch flame generated in the combustion chamber. As the elements 91-94 cool, the coil 80 will, on the other hand, move toward the torch flame axis, thus holding fuel temperatures within preselected limits.

While the principles of the present invention have been described in conjunction with a portable torch, the invention may be applied to pressure stoves designed to burn liquid hydrocarbon fuels bearing non-vaporizable additives or elements and to other types of burners for projection-combustion of fuels of this type. A liquid fuel burner has thus been described which is capable of producing instantaneous heat and of producing heat from a burner of the fuel-vapor type without air being pre-mixed with the fuel once the burner has reached a predetermined level of operation. A control element has also been provided which, through adjusting means and a thermal motor, permits partial, but not complete, vaporization of liquid fuel, so that standard hydrocarbon liquid fuels can be employed without objectionable deposits of gums, resins, or other non-volatilizable fractions or additives being deposited out or left behind in the relatively narrow passages of the fuel vaporizing system.

In accordance with the patent statutes, the principles of the present invention may be utilized in various ways, numerous modifications and alterations being contemplated, substitution of parts and changes in construction being resorted to as desired, it being understood that the embodiment shown in the drawings and described above and the particular control and burning method set forth are given merely for purposes of explanation and illustration without intending to limit the scope of the claims to the specific details disclosed.

What we claim and desire to secure by Letters Patent of the United States is:

1. A portable torch for vaporizing and burning liquid hydrocarbon fuel, said torch comprising a sealed container for holding a supply of fuel and a charge of air under pressure, a metal block formed to define a mixing chamber, means defining separate passages through which fuel and air are conducted under pressure from the supply container to the mixing chamber, a combustion tube, a nozzle having an orifice through which fuel is projected into the combustion tube, means located exteriorly of the combustion tube defining a fuel passage from the mixing chamber to the nozzle and including a heat ex-

13

changing element, means supporting the heat exchange element in heat exchange relation to the torch flame resulting from ignition of projected fuel, and thermal responsive means in direct heat exchange relation to and subject to the temperature of fuel in a portion of the fuel passage between the heat exchange element and the nozzle arranged automatically to vary the heat exchange relation to control the heating of fuel traveling through the fuel passage in obtaining a substantially constant condition in the projected fuel.

2. In a liquid fuel burner of the type comprising means defining a mixing chamber into which fuel and air are projected under pressure to form a pressurized combustible mixture, valve means governing the projection of air into the chamber to vary the fuel-air ratio of the mixture, means defining a jet orifice through which the pressurized mixture is released, means defining a combustion chamber to receive the mixture released from the orifice and having a discharge through which flame and combustion products are projected, means defining a passage from the mixing chamber to the jet orifice, said passage including a portion defined by a tube of high heat conductivity metal, means supporting said tube portion in the path of hot combustion products projected from the combustion chamber discharge, and means responsive to the temperature of the mixture having operative connection with the tube portion supporting means to alter the position of such tube portion relative to the projected hot combustion products, whereby automatically to maintain the condition of the released mixture within predetermined limits.

3. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, conduit means for conducting fuel under pressure from the chamber of the body member to the nozzle, said conduit means including a heater to condition fuel flowing to the nozzle, the heater being exposed to the heat developed in a torch flame from the nozzle, and thermostatic means immersed in and in direct heat exchange relation to heated fuel flowing to the nozzle from the heater, said thermostatic means automatically varying the exposure of the heater in response to changes in the temperature of the fuel flowing to the nozzle to maintain a predetermined condition in fuel discharged.

4. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, a heating element located outside the body member, conduit means connecting the heating element to the chamber of the body member and to the nozzle for serial flow of fuel under pressure from the body member chamber to the heating element and from the latter to the nozzle, the heating element being arranged so as to be heated by the heat developed in a torch flame from the nozzle to condition fuel flowing to the nozzle and supported for movement relative to the nozzle and such a torch flame, and thermostatic means operatively connected to the heater and disposed in heat exchange relation to heated fuel flowing from the heater to the nozzle, said thermostatic means being adapted to effect such movement of the heater in accordance with temperature changes of such heated fuel in governing the heating of the heating element in response to the temperature of the fuel moving to the nozzle whereby automatically to maintain a predetermined condition in fuel discharged from the orifice of the nozzle.

5. In a liquid fuel burning structure of the type comprising a body member formed with an internal chamber to which liquid fuel is supplied under pressure and a hollow nozzle mounted on the body member and hav-

14

ing an outlet orifice through which the fuel is discharged under pressure to burn as a torch flame upon ignition, conduit means for conducting fuel under pressure from the chamber of the body member to the nozzle, said conduit means including a plurality of flexible sections and a heater section substantially wholly supported by the flexible sections in the normal path of a torch flame from the nozzle to absorb part of the sensible heat of such flame and thereby heat and partially vaporize the fuel being conducted to the nozzle, and adjustable supporting means for the flexible sections of the conduit means whereby to alter the position of the heater section relative to such torch flame to vary the ratio of flame heat absorbed by the heater section of the conduit means to the total heat of the torch flame.

6. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, conduit means for conducting fuel under pressure from the chamber of the body member to the nozzle, said conduit means including a heater section and flexible support sections, at least one of the support sections being fast to the body member, the heater section being substantially wholly supported by the support sections in the normal path of a torch flame from the nozzle to absorb part of the sensible heat of such flame and thereby heat and partially vaporize the fuel being conducted to the nozzle, and means having connection with the conduit means and responsive to the temperature of heated and partially vaporized fuel acting automatically to alter the position of the heater section relative to such torch flame whereby to vary the ratio of flame heat absorbed by the heater section of the conduit means to the total heat of the torch flame.

7. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, conduit means for conducting fuel under pressure from the chamber of the body member to the nozzle, said conduit means including a heater section and flexible support sections, at least one of the support sections being fast to the body member, the heater section being substantially wholly supported by the support sections in the normal path of a torch flame from the nozzle to absorb part of the sensible heat of such flame and thereby heat and partially vaporize the fuel being conducted to the nozzle, and a thermostatic element located in direct heat exchanging relation to heated and partially vaporized fuel in one of the flexible support sections, said thermostatic element being responsive to an increase in temperature of such fuel to act automatically to shift the conduit means to alter the position of the heater section relative to such torch flame whereby to vary the ratio of flame heat absorbed by the heater section of the conduit means to the total heat of the torch flame.

8. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, conduit means for conducting fuel under pressure from the chamber of the body member to the nozzle, said conduit means including a heater section and flexible support sections, at least one of the support sections being fast to the body member, the heater section being substantially wholly supported by the support sections in the normal path of a torch flame from the nozzle to absorb part of the sensible heat of such flame and thereby heat and partially vaporize the fuel being conducted to the nozzle, means having connection with the conduit

75

means and responsive to the temperature of heated and partially vaporized fuel acting automatically to alter the position of the heater section relative to such torch flame whereby to vary the ratio of flame heat absorbed by the heater section of the conduit means to the total heat of the torch flame, and means connected between the conduit means and the body member and actuatable manually for shifting the heater section relative to such torch flame to adjust the relation between the heater section and the torch flame.

9. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, conduit means for conducting fuel under pressure from the chamber of the body member to the nozzle, said conduit means including a heater section disposed in the path of a torch flame from the nozzle and a flexible section connected between the body member and the heater section to permit shifting of the heater section into and out of the torch flame, the flexible section comprising a corrugated tube having a continuous spiral internal groove, and an element extending through the center of the corrugated tube constraining the fuel to flow circumferentially in the spiral groove.

10. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, conduit means for conducting fuel under pressure from the chamber of the body member to the nozzle, said conduit means including a heater section disposed in the path of a torch flame from the nozzle and a flexible section connected between the body member and the heater section to permit shifting of the heater section into and out of the torch flame, the flexible section comprising a corrugated tube having a continuous spiral internal groove, a bimetallic strip extending through the center of the corrugated tube in direct heat exchanging relation to fuel flowing therethrough, said strip being characterized by bending in one direction during an increase and in another direction during a decrease in its temperature thereby to effect corresponding bending of the corrugated tube and said shifting of the heater section, and said strip being in contact with the internal surfaces of the tube corrugations whereby to constrain the fuel to flow circumferentially in the spiral groove.

11. In a liquid fuel burning structure of the type comprising a body member formed with an internal chamber to which liquid fuel is supplied under pressure and a hollow nozzle mounted on the body member and having an outlet orifice through which the fuel is discharged under pressure to burn as a torch flame upon ignition, conduit means for conducting fuel under pressure from the chamber of the body member to the nozzle, said conduit means including a heater section and flexible support sections, at least one of the support sections being fast to the body member, the heater section being substantially wholly supported by the support sections in the normal path of a torch flame from the nozzle to absorb part of the sensible heat of such flame and thereby heat and partially vaporize the fuel being conducted to the nozzle, a thermostatic element located in direct heat exchanging relation to heated and partially vaporized fuel in one of the flexible support sections, said thermostatic element being responsive to an increase in temperature of such fuel to act automatically to shift the conduit means to alter the position of the heater section relative to such torch flame whereby to vary the ratio of flame heat absorbed by the heater section of the conduit means to the total heat of the torch flame, and heat insulation embracing said one flexible support sec-

tion to restrict the thermostatic element to temperature effects resulting from fuel in the one flexible support section.

12. A liquid fuel burner comprising a supporting structure, a nozzle carried by the supporting structure, means supplying fuel to the nozzle under pressure to project the fuel from the nozzle as a spray for burning in the form of a torch flame, the fuel supplying means including a conduit through which the fuel travels on its way to the nozzle, said conduit having a heater section located in a position that is offset laterally relative to the nozzle so as to be subject to a portion of the heat of the torch flame to heat the traveling fuel, and means disposed in direct heat exchange relation to and responsive to the temperature of the fuel traveling in the conduit between the heater section and the nozzle automatically varying the heating of the heater section by the torch flame in accordance with temperature changes in such last mentioned travelling fuel to maintain the fuel supplied to the nozzle at a substantially constant predetermined temperature.

13. A unitary readily portable liquid fuel burning structure for vaporizable hydrocarbon fuels, said structure comprising in combination a tank adapted to contain a supply of liquid fuel and a volume of compressed air above the fuel, a body member mounted on the tank and formed with an internal chamber, means providing separate passages for conducting fuel and air under pressure from the interior of the tank to the chamber in said body member, a nozzle carried by the chambered body member and formed with an outlet orifice through which to project a combustible mixture of fuel and air to burn as a torch flame upon ignition, conduit means including sections outside the body member providing a passage for conducting a mixture of fuel and air under pressure from the chamber to the nozzle, one of said outside sections of the conduit means being a heater section through which the mixture flows, means carried by the chambered body member and connected to the outside sections of the conduit means to support the latter with the heater section positioned in the path of the torch flame, said last named means being adjustable to shift the position of the heater section relative to the torch flame whereby to vary the heat absorption of fuel flowing through such heater section in regulating the degree of fuel vaporization to prevent overheating of the fuel and carbonization.

14. The method of burning liquid hydrocarbon fuel having nonvaporizing constituents in a fuel burner of the type having nozzle formed with an orifice through which the fuel is discharged to burn as a torch flame when ignited, which method comprises conducting the fuel to the nozzle under pressure substantially continuously at substantially a constant rate and over a predetermined path, discharging the fuel from the nozzle orifice, igniting the discharged fuel to produce a steady torch flame, exposing the fuel in one portion of said path to the heat of the torch flame to heat and effect partial vaporization of the fuel as it is conducted to the nozzle, and continuously regulating the exposure of the fuel to the torch flame heat in response to the temperature of the heated and partially vaporized fuel to maintain the temperature of the fuel being discharged within predetermined limits.

15. The method of burning liquid hydrocarbon fuel having nonvaporizing constituents in a fuel burner of the type having a nozzle formed with an orifice through which the fuel is discharged to burn as a torch flame when ignited, which method comprises conducting the fuel to the nozzle under pressure substantially continuously at substantially a constant rate and over a predetermined path, discharging the fuel from the nozzle orifice, igniting the discharged fuel to produce a steady torch flame, exposing the fuel in one portion of said path to the heat of the torch flame to heat and effect partial vaporization of the fuel as it is conducted to the nozzle, passing the heated and partially vaporized fuel in heat

exchanging relation to a heat responsive element in another portion of the fuel path, and continuously regulating the exposure of the fuel to the torch flame heat in accordance with the response of such element to maintain the temperature of the fuel being discharged within predetermined limits.

16. The method of burning liquid hydrocarbon fuel having nonvaporizing constituents in a fuel burner of the type having a nozzle formed with an orifice through which the fuel is discharged to burn as a torch flame when ignited, which method comprises conducting the fuel to the nozzle under pressure substantially continuously at substantially a constant rate and over a predetermined path, discharging the fuel from the nozzle orifice, igniting the discharged fuel to produce a steady torch flame, passing the fuel as it is conducted over one portion of the predetermined path in direct heat exchanging relation to the steady torch flame to absorb a fractional portion of the heat of such flame to heat and effect partial vaporization of the fuel, and continuously regulating the heat exchanging relation solely in response to the temperature of the fuel in another portion of such predetermined path to vary the ratio of the flame heat portion absorbed to the total flame heat, whereby to maintain the temperature of the fuel being discharged within predetermined limits.

17. A portable torch for vaporizing and burning liquid hydrocarbon fuel, said torch comprising a sealed container for holding a supply of fuel under pressure; a combustion tube; a nozzle having an orifice through which fuel is projected into the combustion tube; means defining a fuel passage from the container to the nozzle and including a heat exchange element adapted for fuel flow therethrough; means having connection with the container, with the fuel passage defining means and with the nozzle, supporting the heat exchange element in heat exchange relation to a torch flame resulting from ignition of fuel projected from the nozzle; and thermal responsive means directly subjected to the temperature of fuel in a portion of the fuel passage between the heat exchange element and the nozzle and operatively associated with the support means and the heat exchange element arranged automatically to vary said heat exchange relation in response to the temperature of the fuel in said last mentioned passage portion to control the heating of fuel travelling through the fuel passage in obtaining a substantially constant condition in the projected fuel.

18. In a liquid fuel burner, a body member, a nozzle supported by the body member in fixed relation, said nozzle being adapted to receive fuel under pressure and having an orifice through which fuel is discharged to burn as a torch flame upon ignition, a fuel vapor control element comprising conduit means adapted to conduct fuel under pressure from a fuel supply tank to the nozzle, said conduit means including a heat absorbing portion and a flexible connecting portion, the heat absorbing portion being continuous with and supported by one end of the connecting portion and disposed in the flame path to heat and partially vaporize fuel flowing therethrough to the nozzle, the other end of the connecting portion being held in fixed relation to the body member and connected to the nozzle to deliver fuel to the latter, and a thermal responsive element carried by the flexible connecting portion of the conduit means in heat exchange relation to fuel flowing through the latter, said thermal element bending in response to changes in its temperature and being adapted to effect simultaneous bending of said flexible connecting portion, whereby such bending of the connecting portion varies the position of the heat absorbing portion in and relative to the flame path auto-

matically to adjust the heating of fuel flowing through said heat absorbing portion in response to the temperature of fuel in the flexible connecting portion.

19. In the process of burning as a torch liquid hydrocarbon fuel having vaporizable and non-vaporizable constituents which comprises conducting the fuel under pressure along a predetermined path of relatively small cross sectional area having heat conducting walls to a projection orifice, continuously discharging the conducted fuel from the orifice into a combustion supporting atmosphere, igniting the discharged fuel to produce a steady torch flame, and heating by conduction through such walls and vaporizing the fuel in said path and by said flame before the fuel is discharged, the improvement which comprises automatically moving the conductive walls defining the fuel path laterally relative to the direction of the torch flame and relatively into and out of such flame to vary the heating to vaporize a portion only and to prevent complete vaporization of the vaporizable constituents whereby the unvaporized vaporizable constituents constitute and until discharged are maintained as a liquid vehicle entraining the non-vaporizable constituents and preventing depositing of the latter as a residue along said path.

20. The improvement in the fuel burning process as defined in claim 19 wherein the varying of the heating is thermostatically effected.
